UNITED STATES PATENT OFFICE.

ARVID EK, OF PORTLAND, MAINE.

WATER CLOSET.

1,402,850.

Specification of Letters Patent. Patented Jan. 10, 1922.

Application filed May 21, 1917, Serial No. 169,838. Renewed September 25, 1919. Serial No. 326,383.

To all whom it may concern:

Be it known that I, ARVID EK, a citizen of the United States, residing at Portland, in the county of Cumberland and State of Maine, have invented certain new and useful Improvements in Water Closets, of which the following is a specification.

My invention relates to a water closet, having a low seat whereby the person using it will be obliged to assume a crouching position.

It is a physiological fact that the natural position to assume in evacuating the rectum is a stooping or crouching position.

15 In this manner a mechanical pressure is put on the rectum and the lower colon, whereby the evacuation of the feces is aided and accelerated. This is the position of nature and my invention is directed to produce a water closet which will enable the user to assume this natural position and thereby increase the expulsive forces of the colon thus preventing retention of fecal matter therein, as it is a known fact that 25 persons using this crouching or natural position are less troubled with constipation than others using the high seat now in general use.

It is necessary to have a certain distance 30 from the seat to the lower end of the trap in order to provide room for the trap, so that in order to make the seat a low one, with respect to the user, I form on the sides of the closet, a raised platform or foot rest. 35 In this way plenty of room is given for the formation of a trap between the floor and the seat.

A low closet of this character with raised foot rests is much better applicable to a 40 narrow closet adapted to be straddled and consequently, I form the closet proper relatively long and narrow with straight sides, the closet having the general form of a trough. The foot rest is preferably inclined forward, so as to counteract the tendency to cramp the foot or calf.

It is also intended that this type of closet shall be useful for children as well as adults. Physicians have long been aware 50 that the use of the common high seat closet is improper and injurious for children.

My closet provides the same advantages and benefit for children as for grown-ups. The end of the closet toward the trap where 55 the foot rest is higher from the floor and nearer the seat of the closet would naturally

be adapted for children's use, while the middle and opposite end where the distance is farther between the foot rest and the top of the seat, would be the portion of the 60 seat naturally used by adults.

In the accompanying drawing, I have illustrated a closet constructed in accordance with my invention.

In the drawing,

Fig. 1 is a longitudinal section taken in the center,

Fig. 2 is a plan,

Fig. 3 is a cross-section on the line 1—1 of Fig. 1 and Fig. 4 is a cross section of a 70 modified form of the device showing a narrow channel at the bottom.

Referring to the drawing, 2 is the closet proper, the closet being relatively long and narrow, so that it will pass easily between 75 the legs. Its sides are substantially parallel but may be slightly inclined toward each other leaving a relatively narrow opening 3 between the sides.

The closet is formed with a trap in the 80 usual manner, and it is so constructed that the user is obliged to take a crouching position by forming on each side a foot rest 4, which is raised some distance above the floor. This foot rest is preferably inclined 85 in a forward direction, so as to overcome the tendency of the foot or calf becoming cramped. It also extends along the side of the closet preferably from a point in front to the rear end rising toward the rear end. 90

As here shown the closet and the foot rest are formed integral, the whole structure being made in one piece. The foot rest is made hollow and constitutes in effect an elongated box for the support of the closet 95 proper. The hollow foot rest is strengthened to support the weight of the closet by strengthening partitions, 5 extending across the structure from side to side and taking the form of an arch as shown in Fig. 3. 100

The closet and the platform or foot rest may, if desired, be of separate construction. I have provided holes 8, so that hinges may be affixed for top seat or cover, should either or both be wanted.

In Fig. 4, I show a form in which the edges are made comparatively flat and wide, so that an easy, comfortable seating surface may be obtained. In Fig. 4, 6 represents the closet proper and 7 is the flat side. 110

I claim:

1. A water closet having an elongated

narrow opening with substantially parallel sides, a forwardly sloping foot rest on each side extending the entire length of the opening whereby the height of the seat above the foot rest is graduated to adapt it to children and adults.

2. A water closet of the character described having a relatively elongated bowl portion narrowed transversely, the length and width of the bowl portion being such as to permit users to straddle the same and use the bowl at substantially different points lengthwise of the bowl portion, in combination with means attached to the bowl for supporting the user in crouching attitude at said different points of use.

3. A water closet of the character described having a relatively elongated bowl portion narrowed transversely, the length and width of the bowl portion being such as to permit users to straddle the same and use the bowl at different points lengthwise of the bowl portion, in combination with means for supporting the user in crouching attitude at said different points of use, said supporting means including foot rests at the sides of the bowl portion adapted to be engaged by the user at corresponding different points, the foot rests being positioned in a higher plane with reference to the floor level at one end of the bowl portion than at the other.

4. A water closet of the character described having a base portion, a bowl portion, and supporting means at the sides of

the bowl portion arranged between the base portion and the upper edge of the bowl portion and adapted to be engaged by a user straddling the bowl portion, said bowl portion and supporting means being elongated, 40 and the supporting means being inclined to permit the same to be engaged at different places and the closet to be correspondingly used at different points while supporting the user in different crouching positions.

5. A water closet of the character described having a relatively elongated bowl portion narrowed transversely, the length and width of the bowl portion being such as to permit users to straddle the same and use 50 the bowl at substantially different points lengthwise of the bowl portion, and supporting means for the user arranged with reference to the upper edge of the bowl portion to vary at said different points to correspondingly support the user at different places.

6. A water closet of the character described, having a relatively elongated bowl portion, the length of the bowl portion being 60 such as to permit users to crouch above the same at different points lengthwise of the bowl portion, and supporting means at different elevations at the sides adapted to sustain the user at correspondingly different 65 places.

In testimony whereof I hereby affix my signature.

ARVID EK.
